UNITED STATES PATENT OFFICE.

ERNEST M. WHITNEY, OF PROVIDENCE, RHODE ISLAND.

SEPARABLE FASTENER.

Application filed December 21, 1925. Serial No. 76,651.

My invention relates to separable fasteners of the type comprising series of interlocking units longitudinally disposed upon the adjacent edges of material lengths, 5 and engaged or disengaged by a slidable member movable in opposite directions upon units. The material lengths may be embodied in footwear, bags, pouches, garments and other articles.

10. The essential objects of my invention are security of engagement of the interlocking units with each other and with the slidable member under all conditions; facility of interengagement and release of the interlocking units; the prevention of accidental movement of the locking member at any determined point of its travel as well as insurance against accidental escape; and the attainment of these ends in a simple and 20 inexpensive structure.

To the above ends essentially my invention consists in such parts and in such combinations of parts as fall within the scope of the appended claims.

25. In the accompanying drawings which form a part of this specification—

Figure 1 is a front elevation of a fastener embodying my invention,

Figure 2, a similar fragmentary elevation 30 of the same, the front of the slidable member being broken away, as well as certain of the interlocking units,

Figures 3 and 4, sections taken on lines 3—3, 4—4, respectively of Figure 1, and

35. Figures 5 and 6, side elevations of the receiving and entrant locking members respectively.

Like reference characters indicate like parts throughout the views.

40. In the form of my invention herein shown 10 represents the material lengths to the margins of which my fastener is applied. Herein the adjacent edges of the lengths are folded to form longitudinal shouldered edge portions 11. Interspaced from each other in longitudinal series upon one of the edge portions are interlocking receiving units or posts represented generally by the reference character 13. Each of these comprise a

45. substantially rectangular oblong body 14 with a rounded forward end 15 and a rear end recessed or bifurcated as at 17 to form jaws 18 for engaging one of the shouldered portions 11 of the lengths 10. Near its 50 outer end the body has a transverse hole 20 extending between the lateral faces at the

end of the body of the former, while upon the top and bottom faces are cylindrical guide posts or trunnions 22 in transverse alignment with the holes. 60

Upon the adjacent edge of the opposite length are a longitudinally disposed series of interlocking entrant units 24 arranged in staggered relation to the units 13. Each unit 24 has an oblong rectangular body 25 65 recessed as at 26 to form rearwardly directed jaws 27 to engage the edge portion 11 of the second length 10. The forward end of the body is arched and laterally extended to form oppositely directed shoulders 29 comprising plane rear faces disposed at right angles to the body, and arcuate front faces, and adapted to rock into the holes 20 of the adjacent receiving members. Upon the top and bottom of the end of the body 25 70 are posts or trunnions 31 in the transverse plane of the shoulders so disposed as to be in serial longitudinal alignment with the posts 22 when the units 13 and 24 are interengaged. 75

80. A slide 32 for controlling the interlocking units comprises a bottom plate 33 connected with a parallel top plate 34 by a neck 35 at its upper end. A staple 36 disposed centrally of the slide near its upper end has its legs 37 fast in the bottom plate and extending through holes 38 in the top plate, and its loop 39 projecting from the latter. The inner faces of both plates have Y shaped 85 grooves 40, the diverging arms of which enclose the portions 37 of the staple. Slidably mounted on the latter is a flat lever or finger piece 42 having cut and bent from the material of its central portion a resilient longitudinally disposed tongue 43 having upon 90 its free end a rearwardly directed finger 44 extending through an opening 45 in the plate into one of the grooves 40. The posts 31 register in the grooves 40 hence the finger 44 is in the path of the advancing posts, and intercepts the movement of the slide. 95 when the lever is depressed as described. The end of the lever 34 has a cam projection 46 engageable with the top plate, and adjacent the former is a hole 47 to admit loosely therethrough the loop 39. It is evident, therefore, that the lever 42 may be manually moved in an arc to and from the plate 34, and be held in contact with the latter by the cam. If, as the finger 44 advances, its 100 end in the first instance strikes the end of a post 31 the resiliency of the tongue 43 105 110

will cause it to yield, as shown in broken lines in Figure 3, until the post has passed and then snap into locked position.

In order to stop the travel of the slide 5 a plurality of units 48, 49, and 50 are arranged in contact with each other upon one of the lengths, 48 and 50 being of receiving unit construction, and 49 being of entrant construction. It is evident that as the slide 10 advances over these three stop units one of the opposite units 24 will be blocked against engagement and thus prevent progress of the parts.

51 represents a wire binder or loop engaging and closing the lower ends of the lengths.

It will be observed that the arcuate construction of the front faces of the free ends of the units 24 combined with the right 20 angular disposition of their rear faces facilitate their entrance into the adjacent cavities and insures a rigid seating in the engaged units.

The presence of the posts or trunnions 31 25 and their movement through the grooves 40 form a positive and strong guide, and afford perfect interlocking movement of the units. The posts and groove construction also enable the slide to be of smaller dimensions than is the case where, as heretofore, 30 the slide was required to extend across and entirely enclose both series of units.

The slide as thus constructed insures a firm lock against accidental sliding, a result impossible where the friction of compressed plates is employed for this purpose.

I claim:—

1. In a separable fastener, material 40 lengths, interlocking receiving units upon one length provided with lateral holes in their end portions, posts upon the top and bottom of the units in transverse alignment with the holes, interlocking entrant units disposed upon the other material length in alternate relation to the first units, lateral shoulders upon the second units adapted to register in the holes of the first units, posts upon the end portions of the second units in the transverse plane of the shoulders, and a 45 slide adapted to successively engage the interlocked units provided with a groove adapted to guide and align the posts upon the first and second units in a single longitudinal series.

2. In a separable fastener, material lengths, interlocking receiving units upon one length provided with lateral holes, interlocking entrant units upon the second length staggered with relation to the receiving units, shoulders upon the sides of the entrant units registerable in the holes of adjacent receiving units, posts upon the receiving units and entrant units, a slide comprising rigidly connected plates provided with guide channels upon their inner faces adapted to receive the posts, one of said plates being provided with an opening, a lever pivotally mounted upon the last mentioned plate, and a finger carried by the lever adapted to enter the opening in the path of the posts.

3. In a separable fastener, material lengths, interlocking receiving units upon one length provided with lateral holes, interlocking entrant units upon the second length, lateral shoulders on the entrant units registerable in the holes, posts upon the receiving and entrant units in longitudinal series, a slide comprising an upper plate provided with a Y shaped groove adapted to slidably receive certain of the posts, a lower plate provided with a groove adapted to receive the remaining posts, said upper plate being provided with an opening extending into the first groove, a staple loop on the upper plate, a lever provided with a hole through which the loop loosely passes, a cam on the lever within the loop, a resilient tongue integral with the lever, and a finger on the tongue extending through the last mentioned hole into the path of the posts.

4. In a separable fastener, material lengths, interspaced interlocking units extending throughout the extent of one length, interspaced interlocking units extending throughout a portion of the extent of the other length in staggered relation to a part of the first units, a plurality of noninterspaced like, fixed units upon the remaining portion of the second length opposite the remainder of the first units and in contact with each other, and a slide slidably mounted upon the units.

In testimony whereof I have affixed my 100 signature.

ERNEST M. WHITNEY.
